HENRY C. HOOK, OF WINDSOR, VERMONT, ASSIGNOR, BY MESNE ASSIGNMENTS, TO
ALUMINUM MANUFACTURES, INCORPORATED, OF CLEVELAND, OHIO, A CORPORA-
TION OF DELAWARE.

BLANK HOLDING AND EJECTING MECHANISM.

1,426,738.

Specification of Letters Patent. Patented Aug. 22, 1922.

Application filed August 30, 1920. Serial No. 407,029.

To all whom it may concern:

Be it known that I, HENRY C. HOOK, a citizen of the United States, residing at Windsor, in the county of Windsor, State of Vermont, have invented certain new and useful Improvements in Blank Holding and Ejecting Mechanism, of which the following is a specification, reference being had therein to the accompanying drawings.

10 This invention relates to blank holding and ejecting mechanism for presses and the like, and is especially concerned with a device for holding cylindrical bushing blanks on the platen of a press in position for interior broaching operations, and subsequently ejecting the blanks.

It has for its principal object the provision of a simple, improved holding and ejecting mechanism for presses and the like, 20 which may be fed manually with ease and safety to the operator, which will correctly position and hold the blanks on the platen of the press, and automatically eject the blanks from the press.

25 Other objects will be pointed out in the following specification and claims.

To enable others to practise my invention I will now describe a practical embodiment of it, reference being had in the description 30 to drawings attached to and forming a part of this specification in which,

Fig. 1 is a top plan view of the blank holding and ejecting mechanism.

Fig. 2 is a sectional view taken on line 35 2-2, Fig. 1, showing portions of the press with which my device is connected and operates.

Fig. 3 is a side elevation taken on line 3-3, Fig. 1, in the direction of arrows.

40 Fig. 4 is a detail view of the movable spring member and its mounting, taken on line 4-4, Fig. 1.

Fig. 5 shows the position of the various parts of my device when the broach is being retracted from the bushing.

1 indicates the uprights of an ordinary vertical crank type press, such as may be used for broaching operations, and 2, 3, 4, and 5 indicate, respectively, a reciprocating press head, a broach, a cross bar or stripper, and a bolster plate, forming parts thereof. 50 Other parts of the press are not shown or described since they are well known and are

not directly connected with or modified by my device.

A table or platen 5^a is secured between uprights 1 and on bolster plate 5 of the press. It may consist of one part, but is preferably provided with a central circular opening 6, having a shoulder 7 near its upper surface to receive and support an adaptor 8. This adaptor is centrally bored as at 8^a to permit the broach 3 to pass through without engagement with the sides thereof. The size of the opening 8^a, however, should be only slightly larger than the broach since the blank or bushing 9 is supported by the platen and adaptor during broaching. Adaptors having different sized openings, suitable to bushings and broaches 70 of various sizes can be mounted in the platen and will quickly adapt the press to blanks of any desired size.

10 indicates a flat plate adjustably secured to the platen 5^a by cap screws 11 passing through slots 11^a, in the plate. The heads of screws 11 contact with shoulders 11^b formed in slots 11^a, and are so proportioned in size that their top surfaces do not project above the top surfaces of plate 10. Edges 80 or surfaces 12 and 13 respectively of plate 10, serve to guide the bushing toward the opening 8^a and to position it accurately about the opening in operative position for broaching.

Surface 13 comprises two straight portions 13^a and 13^c arranged at substantially right angles to each other and united by a curved portion 13^b. When plate 10 is moved relative to platen 5^a, as screws 11 and slots 90 11^a permit, the surface 13 will be suitably disposed relative to opening 8^a to accurately position and hold circular blanks of various sizes for broaching or other operations, the curved surface, 13^b, being always located as 95 part of a circle described about the center of opening 8^a.

At the rear side of platen 5^a, a vertical post 14 having screw threaded engagement therewith pivotally carries a collar 14^a and 100 an L shaped arm 15. A flat sheet metal member 16 is suitably secured to the arm 15, one end being perforated to receive the loop of a coiled spring 17, the other end of which is held by a post 18 mounted on 105 platen 5^a. Movement of arm 15, caused by

spring 17, is limited by an adjustable screw 19, which passes through arm 15 and contacts with post 20 secured to the platen 5^a. The other end of member 16 which extends 5 well beyond the corresponding end of arm 15 is suitably bent at points adjacent opening 8^a to form a plurality of straight blank holding portions or surfaces 16^a, 16^b, and 16^c inclined to each other and capable of 10 co-operation with plate 10 to position and hold a blank on platen 5^a suitably, for broaching. A lip 22, depending from one of these surfaces, 16^b, is offset toward plate 10 for a purpose later to be described. The 15 free end 16^d of member 16 which constitutes an essential part thereof bends back from the blank holding portion 16^c at an acute angle to provide a guiding surface for the blank when it is being fed into 20 the holding device.

The dotted lines, Fig. 1, show the position of parts of the device before a blank has been inserted therein. To insert a blank, it is placed on the platen 5^a and pushed toward 25 opening 8^a and against surface 12 of plate 10. When it contacts with the guiding surface 16^d of member 16, this member pivots on post 14 against the action of spring 17, thus permitting the blank to approach opening 8^a without separate manual movement of member 16. As the blank contacts with surface 13 of plate 10, portions 30 16^a and 22 of member 16 engage it, pressing it into place against surface 13 and about opening 8^a and hold it in operative position for the broaching operation of the press. Surface 16^c assists in positioning the blank on the platen without, however, exerting relatively great pressure on it, while lip 22 35 presses the blank tightly against surface 13 of plate 10. Since the latter surface is relatively narrow as compared with the length of the blank, it is desirable to apply holding pressure to the opposite side of the 40 blank in substantially the same plane as surface 13 to prevent tilting of the blank, as might result if the entire portion of surface 16^b contacted with the bushing. The lip 22 by being located in practically the 45 same plane as plate 10 accomplishes the holding of the bushing without liability of tilting it.

After the downward stroke of the press which forces the broach 3 through the bushing, the broach is retracted by the upward stroke of the press taking with it the blank which clings to it until the stripper 3 separates it from the broach. This action is clearly illustrated in Fig. 5. Projection 55 22 moves underneath the edge of the blank as it is drawn up to the stripper, thus preventing the blank from falling back onto the platen 5^a, when released, and in part supports the blank as member 16 actuated 60 by spring 17, moves it onto the top face 65

of plate 10 out of contact with the press and broach 3.

While I have for purposes of illustration, shown and described a specific embodiment of my invention, I do not wish to be limited thereto since various modifications might be made in the particular device described without departing from the spirit of the invention and the scope of what is claimed. 75

What I claim is:

1. In a blank holding and ejecting mechanism for presses and the like in combination a platen, a plate adjustably mounted thereon and adapted to form a stop for a blank, and a spring actuated member pivotally mounted on the said platen and co-operable with the said plate to retain a blank in operative position relative to the press and to remove the blank after the press has completed its work thereon. 80

2. In a blank holding and ejecting mechanism for presses and the like, in combination, a platen, a member fixedly secured to the platen, a second member movably secured to the platen and adapted to cooperate with the said first member in retaining a blank in operative position on the said platen, the said second member being adapted to eject the said blank over the first member after it has been removed from between the said members, and means for removing the blank from between the said members. 90 95

3. In a blank holding and ejecting mechanism for presses and the like in combination, a blank supporting platen, means for holding a blank in operative position thereon and for ejecting it therefrom comprising a spring member having a depending portion adapted to engage the blank and hold it in operative position and to project beneath the blank during the upward stroke of the press thereby supporting the blank in part during ejection. 100 105

4. In a blank holding and ejecting mechanism for presses and the like, in combination, a blank supporting platen, a plate adjustably secured to the platen and having relatively narrow blank engaging surfaces, a spring actuated member pivotally mounted on the platen and having a relatively wide blank engaging surface and a relatively short, narrow blank engaging surface projecting from the lower edge of the said spring member and offset relative thereto 115 120 to engage a blank in a plane with the said narrow surfaces of the plate.

5. In a blank holding and ejecting mechanism for presses and the like in combination, a platen, two members mounted thereon 125 and adapted to retain a blank in operative position on the platen, one of the members being adapted to move the blank laterally across the other member when it is removed from between the two members by the press. 130

6. In a blank holding and ejecting mechanism for presses and the like, in combination, a platen, two cooperating members mounted on the platen in different horizontal planes, one member having a depending portion in the same plane as the other member and adapted to cooperate therewith to retain a blank in operative position, the said depending portion being adapted to assist in moving a blank out of operative position after a press operation has been performed thereon.

7. In an apparatus for broaching cylindrical bushings, in combination, a press having a reciprocating head, a broach secured therein, a platen having an aperture in alignment with the said broach, a stripper above the platen, members mounted on the platen and adapted to support a cylindrical bushing in alignment with the said broach,

one of the said members being adapted to eject the bushing after it has been released from the broach by the stripper.

8. In an apparatus for broaching elongated cylindrical blanks in combination, a reciprocating broach, a platen having an aperture in alignment with the said broach, a stripper above the platen and adapted to remove blanks from the broach after broaching, a plate having a narrow, blank engaging surface adapted to position a blank adjacent the said aperture for broaching, and a spring pressed member adapted, when cooperating with the said plate, to retain a blank in broaching position and adapted, when acting alone, to eject a blank when the latter is removed from the broach.

In testimony whereof, I hereunto affix my signature.

HENRY C. HOOK.
